[57] CLAIM

The ornamental design of a traffic post, substantially as shown and described.

DESCRIPTION

FIG. 1 is a perspective view showing the traffic post of our new design.

FIG. 2 is a side elevational view thereof on an enlarged scale.

FIG. 3 is a top plan view on an enlarged scale.

FIG. 4 is a bottom plan view on an enlarged scale.

FIG. 5 is a vertical sectional view on an enlarged scale.

The sides not shown are substantially identical with the side shown in FIG. 2.
